UNITED STATES PATENT OFFICE.

BARNETT GERSHOVITZ, OF CANTON, OHIO.

COMBINED MOP AND WRINGER.

Application filed January 31, 1927. Serial No. 164,733.

The invention relates to mops and more particularly to a mop provided with a wringing device thereon.

The object of the improvement is to provide a combined mop and wringer in which any ordinary pieces of rags may be quickly and readily attached, and whereby the mop cloth may be easily wrung without removal from the mop.

10 An embodiment of the invention is illustrated in the accompanying drawing, in which

Figure 1 is a perspective view of the improved mop;

15 Fig. 2 a bottom plan view of the frame, and

Fig. 3 a fragmentary longitudinal sectional view through the frame.

Similar numerals refer to similar parts 20 throughout the drawing.

The mop cloth 1 is adapted to be attached to the handle 2 by running the cloth through the loop 3 upon the crank handle 4, journaled through the mop handle 2.

25 The ends of the mop cloth are adapted to be passed through the loop 5 and clamped between the jaws 6 of the holder indicated generally at 7.

These jaws are connected at their rear 30 edges by the folded plate 8 having the eye portion 9 through which a pin 10 is passed, said pin being pivotally connected at the bifurcated ends 11 of the clamping lever 12.

The loop 5 may have the coils 13 therein 35 to provide sufficient resilience and the ends thereof are passed through openings 14 in the bifurcations 11 of the lever 12 and bent as at 15 to prevent disengagement.

A wire holder 16 is provided at its rear 40 end with the loop 17 and connected to a plate 18 as by the overturned tangs 19, the forward ends of said holder being curved around the lever 12 as shown at 20 and con-

nected to the jaws 6, upon each side of the plate 8 as indicated at 21.

The plate 18 is provided with the upturned ears 22 pivotally connected, as by the pin 23 with the side flanges 24 upon the link 25, the upper end of which is pivoted to the handle 2 as by the pin 26.

After the mop cloth has been attached as above described, the mop is placed in the position shown in Fig. 1 for use, downward or forward pressure upon the handle 2, causing the wire holder 16 to lay flat upon the floor, flattening the mop cloth and holding it to the floor during the mopping operation.

When it is desired to wring the mop, the handle may be raised to a substantially horizontal position, permitting the wire holder 16 and clamping jaws 6 to hang vertically from the link 25. The crank handle 4 may then be turned, twisting the mop cloth and wringing the water from the same.

When it is desired to remove the cloth it 65 is only necessary to swing the lever 12 into the dotted line position shown in Fig. 3, moving the loop 5 out into the dotted line position shown in said figure, permitting the end of the mop cloth to be easily removed and a new cloth to be replaced and clamped 70 therein by swinging the lever back to the normal position.

I claim:

A mop including a handle, a link pivotally 75 connected thereto, a holder pivotally connected to the link intermediate its ends, a pair of jaws carried by the forward end of the holder, a loop arranged to be drawn between the jaws for clamping a mop cloth, a 80 lever upon the holder for operating the loop, a crank carried by the handle and a loop upon the crank for receiving the mop cloth.

In testimony that I claim the above, I have hereunto subscribed my name.

BARNETT GERSHOVITZ.
